[57] CLAIM

The ornamental design for a van, as shown and described.

DESCRIPTION

FIG. 1 is a side elevational view of a van showing my
new design;

FIG. 2 is an end elevational view thereof;

FIG. 3 is a top plan view thereof;

FIG. 4 is a side elevational view thereof as seen from
the side opposite the view shown in FIG. 1;

FIG. 5 is a front elevational view thereof;

FIG. 6 is an enlarged fragmentary elevational view
showing the lower rear portion of the side window and
rear side panel of the van in detail; and

FIG. 7 is an enlarged fragmentary elevational view
showing the lower rear portion of the opposite side
window and rear side panel of the van in detail.

The characteristic feature of my design resides in the
horizontally elongated windows along the sides of the
van.
